WEFT REPLENISHING LOOM STRUCTURE

William E. Lundgren, Auburn, Mass., assignor, by
mesne assignments, of one-half to Sutton Tool
Co., Inc., Wilkinsoerville, Mass., a corporation
of Massachusetts

Application May 26, 1933, Serial No. 672,936

13 Claims. (Cl. 139—258)

This invention relates to an improved weft replenishing loom structure and more particularly to certain novel combinations and arrangements of parts in a weft replenishing loom of the stationary magazine type for effecting the appropriate tensioning of the weft thread with certainty and in such a manner as to render the same effective immediately after transfer.

In the use of weft replenishing looms of the stationary magazine type, as heretofore employed, it has been the practice to provide stationary magazines having one or more compartments, each provided with a support and release mechanism for permitting the release of a bobbin for movement into position for transfer from one or another of said compartments, dependent upon the color desired, through the actuation of suitable selector means controlling the operation of the release mechanism. In this as in other types of replenishing looms as heretofore employed, however, it has been impossible to provide a suitable and appropriate tensioning of the weft thread immediately after transfer in such a manner as to insure adequate and uniform tension on the first pick after transfer. This failure to provide adequate means for tensioning the weft thread immediately after transfer to the shuttle has resulted in serious imperfections in certain classes of woven fabrics such as are adapted to be formed on looms of this character.

One object of the invention is the provision in a loom structure of this character of means for employing a positive tensioning member in association with a transferable bobbin, together with means for utilizing the same as replenishable elements in connection with the usual replenishable shuttles.

Another object of the invention is the provision in a loom structure of this character of associated magazine compartments for receiving bobbins and tension members in such a manner as to retain each bobbin in operative relation with its associated tension member or vice versa, together with means for permitting the movement of each bobbin and its associated tension member into position for transfer to a shuttle.

A further object of the invention is the provision of appropriate release mechanism adapted for operation in such a manner as to release each bobbin and its associated tension member from their compartments substantially simultaneously in order to permit proper movement of these parts into position for transfer to a shuttle.

Another object of the invention is the provision in a device of this character of cooperating

guide members arranged in such relationship to each other as to furnish means for guiding a bobbin and its associated tension member into position for transfer to a shuttle while maintaining them in operative relation to each other.

A further object of the invention is the provision in a loom structure of this character of magazine and supply mechanism for furnishing a bobbin and associated tension member in operative relation to each other into position for transfer to a shuttle upon the operation of suitable selector mechanism, together with means for effecting the transfer of the bobbin and tension member to the shuttle substantially simultaneously.

Other objects and advantages of the invention relate to various improved details of construction and novel arrangements of the parts as will be more fully set forth in the detailed description to follow.

Referring to the drawings:

Fig. 1 is a top plan view of a shuttle of the type employed in replenishing looms, illustrating the position and arrangement therein of a bobbin and tension member separately mounted and located in operative position within the shuttle.

Fig. 2 is a top plan view, partially in section of a replenishable shuttle, showing a bobbin and a tension device associated therewith in such a manner as to be carried by the bobbin on its insertion within or ejection from the shuttle.

Fig. 3 is a side elevational view partially in section, of a portion of a loom of the stationary magazine type, showing a part of a multi-compartment magazine, together with the relation of the several compartments to guide means for guiding associated bobbin and tension members into position for transfer to a shuttle, and the relative position and mode of operation of the transfer member.

Fig. 4 is a horizontal sectional view of the multi-compartment magazine, taken substantially along the line 4—4 of Fig. 3, illustrating the relative form and location of associated bobbin and tension member compartments relative to each other, as well as one arrangement of several sets of associated bobbin and tension member compartments.

Fig. 5 is a perspective view of a portion of the stationary magazine in its relation to the guide means, transfer mechanism and transferable bobbin and tension member, as well as the position and arrangement of certain of the parts in effecting transfer to a shuttle.

Fig. 6 is a detail view, partially in section, taken substantially along the line 6—6 of Fig. 5, and

showing the guide members for guiding the base portion of a bobbin into position for transfer.

Fig. 7 is a detail view, partially in section, taken substantially along the line 7—7 of Fig. 5, and 5 showing the guide members for guiding the tip of the bobbin into position for transfer,

Fig. 8 is a top plan view of one of the combined rocking support and release members for supporting associated bobbins and tension members 10 and effecting their release for transfer at the appropriate point in the loom operation, and,

Fig. 9 is an end elevational view of the same.

In that form of loom structure illustrated herein, 1 designates a portion of the side frame 15 of a conventional type of replenishable loom, having a lay beam 2 provided with a stationary shuttle box 3 located upon one end thereof and arranged in operative relation with a stationary magazine 4. The magazine 4 and its associated 20 mechanism may be supported from a suitable bracket member 5 carried by a part of the side frame and properly arranged with relation to certain of the operating parts of the loom mechanism for actuation thereby at appropriate periods 25 in the formation of the weave, as will be understood by those skilled in the art.

The magazine as shown herein, consists of plates 7, 8 and 9 suitably spaced from each other, and supported in spaced relation with each other 30 by bars 10 and 11, to which they may be fixedly and adjustably secured by bolts 12 and 13, or other suitable fastening means. One or more of the connecting bars 10 and 11 may be formed integral with or secured to the bracket 5 in any suitable 35 manner. The spaced plates 7, 8 and 9 are each provided with suitably positioned vertical ribs 16, 17 and 18, cooperating to form a series of associated compartments, which in the present case are four in number and are designated by the 40 reference characters 20, 21, 22 and 23. Each of these associated compartments, as shown, comprises a bobbin chamber 26 and a tension member chamber 27, the bobbin chamber and tension member chamber in each case being so arranged 45 relative to each other as to hold a plurality of bobbins and associated tension members in vertical columns with each bobbin and its associated tension member arranged in operative relation with each other in such a manner as to be capable 50 of release substantially simultaneously preliminary to their movement into position for transfer. The plates 8 and 9 are provided with vertical slots 30 and 31 respectively, located between adjacent ribs 17 and 18, the slots 30 connecting the bobbin chamber 26 and tension member chamber 27 forming each of the associated compartments 20, 21, 22, and 23. The provision of the slots 30 55 and 31 permits passage of the weft end from each bobbin to its associated tension member and from thence to the thread holding plate 32, and also allows the escape of the weft end from the magazine without injury or breakage upon release of a bobbin and its associated tension member.

60 A combined rocking support and release member 35 is mounted below and in operative relationship with each set of associated compartments, and may be provided with a supporting shaft 36 mounted in a suitable bearing in the plate 7 for actuation by appropriate selector means through a part of the loom mechanism. The member 35 65 comprises a portion 37 adapted to engage and support the base of a bobbin, a bobbin tip holder 38 and a pair of arms 39 shaped to provide a 70 channel-like support for receiving and support-

ing a tension member. The several rocking support and release members 35 are each mounted in operative relation with one of the associated compartments 20, 21 and 22 and 23, and are adapted for operation at suitable points in the formation 5 of the weave to release an associated bobbin and tension member for movement into position for transfer.

Downwardly converging guide members 40 and 41 are located beneath and in operative relation 10 with those portions of the associated compartments located adjacent to the plate 7 to receive and guide the base of each bobbin into position for transfer upon its release by movement of one of the members 35, and similarly arranged guide 15 members 42, 43 and 44, 45 are located beneath and in operative relation with those portions of the associated compartment located adjacent to the plates 8 and 9 to receive and guide the tips of the respective bobbins and the tension members 20 respectively to a position for transfer upon their release by one of the members 35. The guide members 40, 41 and 42, 43 and 44, 45 all converge 25 downwardly and may be resiliently held on pivotal supports 46, by one or more coiled springs 48, 30 to retain an associated bobbin and tension member in alignment with each other above and in appropriate position for transfer to a replenishable shuttle upon actuation of a transfer member 50, as shown in Figs. 3 and 5 of the drawings. 35

The transfer member 50 may be pivotally supported from the frame 5, as at 52, and provided with fork portions 53 and 54 for engagement with the bobbin and tension member respectively to effect their transfer from the guide members to the 40 shuttle substantially simultaneously. The transfer member 50 is provided with a depending arm 56 which is pivotally connected as at 51, with a trip 58, notched at its active face 59, to engage a dagger 60 on the lay beam 2 upon indication of 45 filling replenishment. The lay beam 2 is provided with an opening 62 extending therethrough and positioned to register with the recess in the shuttle body when the shuttle is in replenishing position to permit the ejection of a used bobbin 45 and tension member to a suitable receptacle (not shown), upon transfer.

The type of loom shuttle shown herein is of conventional form in so far as it consists of the usual shuttle body 65 provided with an opening 50 66 extending entirely therethrough to permit the automatic insertion of a bobbin upon one side of the shuttle body and its automatic ejection from the other after a manner well known in devices of 55 this character. The loom shuttle 65, as shown in Fig. 1 of the drawings, is provided at opposite ends thereof with yielding holding jaws 67 having suitable grooves or depressions 68 formed upon their inner surfaces for receiving the usual circular ribs 69 carried by the base 70 of the bobbin 60 71, as well as for receiving similar ribs 72 carried by a separate tension member 73.

As shown in Fig. 1 of the drawings, one form of the invention comprehends the use of a bobbin 71, the base 70 of which is engaged by one set of 65 opposed holding jaws 67 after the usual manner, while its associated tension member 73 is mounted in separated relation with and spaced from the tip 74 of the bobbin spindle, and is similarly positioned within and held by the set of opposed holding jaws 67 located within the opposite end of the opening 66 formed in the shuttle body. The detailed construction and arrangement of the bobbin and tension member, as well as the specific 70 form of construction and arrangement of the 75

parts of the tension member are more particularly set forth in my copending application Serial No. 664,854, to which reference is made for a more detailed description thereof.

- 5 In that form of bobbin and tension member, as shown in Fig. 2 of the drawings, the shuttle body 65 is similar in all respects to that shown in Fig. 1, and is similarly provided with an opening 66 extending entirely therethrough to permit the automatic insertion and ejection of a bobbin, as is well known in devices of this character. The shuttle is provided with a pair of opposed holding jaws 76 located adjacent to one end thereof, each of which has suitable grooves or depressions 78 formed in the inner faces thereof for receiving circular ribs 79 carried by the base portion 80 of the bobbin 81. A circular rib or enlargement 82 is located upon the base portion 80 of the bobbin for engagement with suitable grooves 83 formed in the split resilient end portion 84 of a cylindrical shell 85, which is so formed as to fit over the spindle portion of the bobbin and have the split resilient portions 84 engage over the rib 82 for holding the shell in position upon the bobbin.
- 25 A tension device 86 is mounted within the opposite end portion of the shell 85 and may comprise tensioning members 87 arranged in staggered relation for imparting tension to the weft end 88 carried by the bobbin. Aligned openings 89 and 90 are provided in the tension device 86 for the passage of the weft end from the bobbin to the tension device and from the tension device for incorporation into the fabric. A more detailed description and showing of the parts of the bobbin 81, shell 85 and tension member 86 making up the combined bobbin and tension member 92 is contained in my copending application Serial No. 664,854, to which reference is made.

In effecting the transfer of the bobbin and tension member to and from the shuttle body with that form and arrangement of bobbin and associated tension member as shown in either Figs. 1 or 2 of the drawings, I have provided certain novel means and arrangements of mechanism for supporting these members in replenishing position and for effecting their transfer to the shuttle body while they are maintained in suitable operative relation with each other to insure a proper functioning of the parts immediately after transfer and avoid any tendency which might be present for distortion or disarrangement of the bobbin and tension member relative to each other, either during the act of transfer or as they may be positioned within the shuttle body after transfer. In order to accomplish this purpose effectively, the guide members 40, 41 and 42, 43 may be provided with suitable edge flanges 94 and 95 respectively, which serve to provide with the guide members a complete guideway for each bobbin from its point of release to its transfer position. In a like manner, the tension guides 44, 45 may be provided with flanges 96 located on opposite sides thereof and so spaced from each other as to furnish a guide channel of suitable width for transferring a tension member from its point of release to its point of transfer without permitting its displacement relative to the bobbin.

When a bobbin and its associated tension member are brought into position for transfer to a shuttle, as shown in Fig. 5 of the drawings, they are maintained in transfer position by the resiliently supported guides 40, 41, 42, 43, 44 and 45 until such time as transfer is indicated, when they are forced downwardly substantially simul-

taneously by operation of the transfer member 50 to force the exhausted bobbin and its tension member out of the shuttle body, as shown in Fig. 5, and force the full bobbin and tension member into engagement with the yielding jaws mounted in the shuttle body. Upon discharge of the exhausted bobbin and its associated tension member, the weft end 97 carried thereby is severed and is carried away by the discharged bobbin and tension member, thus preventing it from being drawn into the shed on movement of the replenish shuttle, as the full bobbin and its tension member are inserted into the shuttle, with the weft end 98 carried thereby secured to the thread holder 32 as is usual in the transfer of 15 full bobbins.

In that form of the invention illustrated herein the magazine structure is as shown particularly adapted for use in connection with a separate bobbin and tension member such as is shown in Fig. 1 of the drawings. The magazine, however, is capable of being employed in connection with a combined bobbin and tension member of the type shown in Fig. 2 of the drawings by eliminating the outer plate 9 of the magazine, and spacing the plates 7 and 8 from each other a somewhat greater distance than that shown in Fig. 4, to accommodate the combined bobbin and tension member 92 therebetween.

In making such change the tension member 30 guides 44 and 45 may be omitted, and the guides 42 and 43 set at a greater distance from the guides 40 and 41. In making these changes, modified supporting and release members may be substituted for the supporting and release members 35. 35 As a means for rendering these changes readily effective without basic change in the magazine mechanism and associated parts, the opposed guide members 40, 42, 44 and 41, 43, 45 may be 40 adjustably mounted upon bars, located in parallel relation with each other and upon opposite sides of the replenishable shuttle by set screws or similar means, so that the tension member guides 44 and 45 may be removed readily and the relative location of the guides 40, 42 and 41, 45 43 changed to conform with the over-all length of the combined bobbin and tension member 92.

In either form of the invention it is to be understood that the bobbin employed is a replenishable bobbin having a portion provided with means adapted for direct engagement with or separation from the usual or any suitable form of holding means carried by the shuttle body for permitting direct insertion or ejection of the bobbin into or out of weft thread supporting position within the shuttle, and that wherever the terms "bobbin" or "replenishable bobbin" occurs in the specification or claims it refers to a replenishable bobbin of the type above described.

What I claim is:—

1. In a weft replenishing loom of the stationary magazine type, a shuttle, a plurality of transferable bobbins and separate tension members, means for supporting each bobbin and its associated tension member in axial alignment with each other while the several bobbins and tension members are supported in superposed relation with each other, means for releasing one of said bobbins and its associated tension member to permit movement of said bobbin and its associated tension member into position for transfer while retaining them in operative relationship with each other, and means for transferring said bobbin and its associated tension member to the shuttle substantially simultaneously. 75

2. In a weft replenishing loom of the stationary magazine type, a shuttle, a plurality of transferable bobbins and separate tension members, vertical compartments spaced from each other for supporting a plurality of said bobbins and tension members in positions of axial alignment with each other, means for releasing one of said bobbins and its associated tension member from said compartments simultaneously, means for guiding said bobbin and its associated tension member from their released positions to their transfer positions, and means for transferring said bobbin and its associated tension member to the shuttle substantially simultaneously.
3. In a weft replenishing loom of the stationary magazine type, a plurality of transferable bobbins and associated tension members, a magazine section for bobbins having a plurality of chambers, an auxiliary magazine for tension members having a plurality of chambers corresponding with the number of the bobbin chambers and arranged in cooperative relationship therewith, means for supporting a bobbin and tension member in aligned position within each set of associated chambers, a replenishable shuttle, and means common to two or more sets of said chambers for guiding a bobbin and its associated tension member from any one of said chambers into mutually aligned positions above said shuttle and retaining them in such positions pending transfer to the shuttle.
4. In a weft replenishing loom of the stationary magazine type, a plurality of separate bobbins and their associated tension members, a magazine provided with aligned chambers for receiving said bobbins and tension members respectively, means for supporting the bobbins and tension members in two of said aligned chambers movable to release a bobbin and its associated tension member substantially simultaneously to allow movement of the bobbin and its associated tension member into position for transfer to a shuttle, a replenishable shuttle, separate means for guiding each bobbin and its associated tension member into position for their transfer to the shuttle after their release from the chambers, and means for transferring said bobbin and tension member to the shuttle substantially simultaneously.
5. In a weft replenishing loom of the stationary magazine type, a plurality of transferable bobbins and associated tension members, means for supporting said bobbins and tension members with each bobbin occupying a position in alignment with its associated tension member, said supporting means being movable to release one of said bobbins and its associated tension member, a replenishable shuttle, separate means for guiding said bobbin and its associated tension member upon release by said supporting means into position for transfer to the shuttle, and for retaining them in mutually aligned positions pending transfer to the shuttle.
6. In a weft replenishing loom, a magazine provided with a plurality of vertical bobbin chambers and a plurality of vertical chambers arranged in cooperative relationship with said bobbin chambers for the reception of tension members, a plurality of bobbins and associated tension members arranged in operative relationship with each other and located in said chambers, means for releasing a bobbin and its cooperatively arranged tension member from associated chambers substantially simultaneously to allow said bobbin and tension member to move into position for transfer to a shuttle, a shuttle, means for guiding said bobbin and tension member into position for transfer and means for transferring said bobbin and tension member to the shuttle substantially simultaneously.
7. In a weft replenishing loom, a replenishable shuttle, a magazine provided with a compartment for supporting a plurality of bobbins and their associated tension members in operative relation with each other, one or more bobbins and associated tension members mounted in said compartment, a support for the bobbins and tension members movable to permit substantially simultaneous movement of one of said bobbins and its associated tension member into position for transfer to the shuttle, means for supporting said bobbin and tension member in transfer position relative to the shuttle, and means for moving said bobbin and its tension member from their transfer positions into said shuttle substantially simultaneously.
8. In a weft replenishing loom of the stationary magazine type, vertical chambers located in a common plane and arranged in juxtaposition with each other for supporting a plurality of bobbins and associated tension members in aligned positions relative to each other, a plurality of bobbins and associated tension members supported in said chambers, for intermittent vertical movement, said chambers being provided with vertical openings arranged substantially axially of said bobbins and their associated tension members, and a thread holder located outwardly of said tension member supporting chamber, whereby a weft thread carried by a bobbin may extend through an associated tension member and be secured to said thread holder and be retained in unbroken relation with said bobbin, tension member and thread holder during movement of the bobbin and tension member within said chambers.
9. In a weft replenishing loom of the stationary magazine type, vertical chambers arranged in juxtaposition with each other for supporting a plurality of bobbins and associated tension members in aligned positions relative to each other, a plurality of bobbins and associated tension members located in said chambers for intermittent vertical movement, guide members for guiding said bobbins and their associated tension members from said chambers to a position for transfer to a shuttle, means for releasing one of said bobbins and its associated tension member from said chambers for movement to a position of transfer at a predetermined point in the operation of the loom, said chambers being provided with vertical openings arranged substantially axially of said bobbins and associated tension members, a thread holder located outwardly of said tension member supporting chamber, whereby a weft thread carried by a bobbin may extend through an associated tension member and be secured to said thread holder and retained in unbroken relation with said bobbin, tension member and thread holder during vertical movement of the bobbin and tension member within said chambers and their movement to a position of transfer to a shuttle.
10. In a weft replenishing loom, a vertical magazine, a bobbin and tension member carried by said magazine, supporting means for said bobbin and tension member movable to permit intermittent movement of said bobbin and tension member downwardly of said magazine and their discharge therefrom while constantly occupying a substantially fixed relation with each other, and

resiliently supported guide means for guiding said bobbin and tension member into position for transfer to a shuttle after their discharge from said magazine, a replenishable shuttle, and means 5 for effecting the transfer of said bobbin and tension member from transfer position to said shuttle substantially simultaneously.

11. In a weft replenishing loom, a vertical magazine, a bobbin and a separate, self-contained 10 tension member carried by said magazine in axially spaced relation with each other, a replenishable shuttle adapted to be maintained in operative relation with said magazine during the transfer of a bobbin and tension member to the shuttle, 15 and means for transferring said bobbin and its tension member from said magazine to said shuttle while maintaining them in aligned spaced relation with each other during the transfer.

12. In a weft replenishing loom of the stationary magazine type, a replenishable shuttle, spaced plate members forming vertical bobbin 20 receiving chambers, a plate member cooperating with one of said first named plate members to form vertical chambers arranged in cooperative 25 relation with said first named chambers, means for supporting said plate members in adjusted relation with each other, a plurality of transferable bobbins and associated tension members carried by said first named and said second named 30 chambers respectively, means for releasing a bob-

bin and its associated tension member from cooperating chambers, and means for guiding said bobbin and tension member after their release into position for transfer to the shuttle and for retaining said bobbin and its associated tension member in transfer position pending transfer to the shuttle.

13. In a weft replenishing loom of the stationary magazine type, a replenishable shuttle, spaced plate members forming vertical bobbin 10 receiving chambers, a plate member cooperating with one of said first named plate members to form vertical chambers arranged in cooperative relation with said first named chambers, means for supporting said plate members in spaced relation with each other, a plurality of transferable bobbins and associated tension members carried by said first named and second named chambers 15 respectively, means for releasing a bobbin and its associated tension member from cooperating 20 chambers, means for guiding said bobbin and tension member after their release into position for transfer to the shuttle and for retaining said bobbin and its associated tension member in transfer position pending transfer to the shuttle, 25 and a single transfer member for transferring said bobbin and its associated tension member from transfer position to the shuttle substantially simultaneously.

WILLIAM E. LUNDGREN. 30
